Primary Examiner — Kevin Rudzinski(74) *Attorney, Agent, or Firm* — Sterne, Kessler, Goldstein & Fox P.L.L.C.(57) **CLAIM**

The ornamental design for a display screen or portion thereof with icon, as shown and described.

DESCRIPTION

The FIGURE is a front view of a display screen or portion thereof with icon showing my new design.

The broken lines around the FIGURE show a display screen or portion thereof and form no part of the claimed design.

1 Claim, 1 Drawing Sheet(56)
